Attorney

UNITED STATES PATENT OFFICE.

ANTHONY J. OLDEWURTEL, OF BALTIMORE, MARYLAND.

SAFETY POCKET.

Application filed October 8, 1927. Serial No. 224,930.

The present invention relates to safety devices for the pocket of garments, and the primary object of the invention is to provide a safety pocket or flap for garment pockets wherein articles disposed in the pockets will be securely held against loss or possible theft, and yet allowing for easy access being had to the safety pocket when the wearer desires to remove the article from the pocket.

A further object of the invention resides in the provision of a safety pocket embodying an arrangement whereby the weight of an article in the pocket serves to prevent ready movement of the article out of the pocket.

A further object of the invention is to provide a device of this character which is constructed entirely from a sheet of flexible material, thus not materially reducing the capacity of the usual garment pocket with which the device is associated.

A still further object of the invention resides in the provision of a supplemental safety pocket which may be readily applied to the usual garment pocket without requiring alteration to the garment pocket in any manner, and which supplemental pocket will also serve as a reinforcement for the usual garment pocket.

Other objects and advantages of the invention will be apparent during the course of the following detailed description, taken in connection with the accompanying drawing forming a part of this specification and in which drawing:

Figure 1 is a perspective view of the supplemental pocket and showing the same in an extended position.

Figure 2 is a vertical section through a fragmentary portion of a garment and showing the safety pocket as applied to the usual pocket of the garment.

Figure 3 is a perspective view of the inner side of an ordinary garment pocket shown broken away and illustrating the safety pocket arranged within the usual garment pocket, and with a portion of the safety pocket also broken away for clearly illustrating the position of the locking section of the pocket flap.

Referring to the drawing in detail, and wherein similar reference characters designate corresponding parts throughout the several views, the letter A designates a frag-

mentary portion of a garment having a pocket B of usual construction and with which the improved safety supplemental pocket C has been associated.

The fragmentary portion of garment A has been shown as the rear upper portion of a pair of trousers so that the pocket B represents a rear trouser pocket. The pocket B is of ordinary construction and embodies inner and outer walls 5 and 6 respectively. The upper ends of the walls 5 and 6 are not joined for forming an opening or mouth 7 for the pocket through which articles may be readily placed and removed from the pocket.

Referring now to the supplemental pocket C and which is adapted to be positioned within the usual garment pocket B, the same is preferably formed of a single strip of fabric or other suitably flexible material so constructed as to produce a pocket portion 8 and a flap portion 9. The pocket portion or compartment 8 is formed by doubling one end of the material upon itself and stitching along the side edges and bottom edge as at 10 and 11 respectively, and which stitching as will be observed forms a pocket portion having its mouth 12 opening transversely of the supplemental pocket toward the flap portion 9.

Referring now to the flap portion 9 and which serves as a closure for the pocket portion 8 and also as a means for preventing articles from working upwardly out of the pocket portion, the same is preferably of a width substantially equal to the width of the pocket portion 8 and of a length greater than the height of the pocket portion. This flap portion 9 embodies major and minor flap sections 13 and 14 respectively, with the minor flap section 14 disposed at the free end of the major flap section. The major flap section 13 is of a length substantially equal to the height of the pocket portion 8 and forms a continuation of the rear wall 15 of the pocket portion. The front wall 16 of the pocket portion has its upper edge turned inwardly and stitched as at 17 for preventing wear along the upper edge of the pocket portion. The longitudinal edges of the flap portion 9 are also turned inwardly and stitched as at 18 for reinforcing the side edges.

The minor flap section 14 and which is of a height substantially less than that of the major flap section 13, is of double thickness

material and formed by folding the upper end of the material upon itself for the height of the minor flap section and then stitching the flap along the inner and outer edges as 5 at 20 and 21 respectively, the row of stitching 20 serving to secure the free end of the material to the flap portion at the upper edge of the major flap section 13 while the row of stitching 21 extends along 10 the fold at the upper edge of the flap portion. Extending in angular V-shaped formation across the minor flap section 14 is a reinforcing and stiffening stitching 24 as illustrated in Figures 1 and 3, and which 15 reinforcing stitching extends from the transverse row of stitching 20 to the transverse row of stitching 21. This particular arrangement of the reinforcing stitching 24 aside from serving as a stiffening 20 means for the minor flap section, also serves in a manner to prevent ready withdrawal of the minor flap section from a locking position as illustrated in Figure 2. The manner in which this zig-zag stitching 25 24 aids in retaining the minor flap section in a locked position will be subsequently explained. A sewed fold or tuck 25 is formed transversely of the flap portion 9 at the juncture of the minor and major flap 30 sections, and this sewed fold as will be apparent will serve to normally maintain the minor flap section in overlying relation with the upper portion of the major flap section 13. In Figure 1, the minor flap section 14 has been shown in an extended position relative to the major flap section 13 for more 35 clearly illustrating details of the fold 25.

The supplemental pocket C is preferably 40 of a width substantially equal to the width of the garment pocket B and is preferably inserted into the pocket B with the rear wall 15 of the pocket portion 8 disposed in confronting relation to the inner wall 5 of the pocket B. After the supplemental 45 pocket has been positioned in the garment pocket B, a row of stitching as at 28 in Figure 2 is made at a point along the line 29 in Figure 1 for securing the supplemental pocket within the garment pocket B with the mouth 12 of the supplemental pocket arranged slightly below the mouth 7 of the garment pocket. As in usual practice, the garment material extends slightly below the mouth 7 of the pocket so as to conceal the 55 pocket lining, and it is preferred that the supplemental pocket be stitched along the line 29 to that portion of the garment material which projects below the mouth of the garment pocket.

60 When desiring to place an article such as a bill fold in a secure position within the supplemental pocket against loss or possible theft, the flap portion 9 is first withdrawn and then the article inserted into the pocket 65 portion 8 and after which the flap portion

9 is tucked downwardly into the pocket portion and then the stiffened minor flap section worked under the object as in Figure 2 until the stiffened minor flap section is disposed at the rear side of the object between 70 the lower portion of the object and the rear wall 15 of the pocket portion 8. In this position it will be seen that the weight of the article will hold the minor flap or locking section 13 in position and against being withdrawn from the pocket portion 8 without applying some amount of pull upon the flap portion 13. When the locking flap section 14 is in a position between the article and rear wall 15 of the pocket 8, the V-shaped arrangement of stitching 24 will 75 form shallow V-shaped pockets which when pressed against the rear pocket wall 15 will further aid in preventing movement of the locking section downwardly and about the 80 under side of the object being supported in the pocket. When a person wearing the garment supplied with the supplemental pocket desires to remove the article from the pocket, it is merely necessary to grasp the 85 flap portion 9 when it is looped above the article and exert sufficient pull upon the flap to cause the locking section 14 to be withdrawn from beneath the object, and it will readily be seen that an unauthorized person could not readily remove the object from the supplemental pocket without attracting the attention of the person owing to the required pull necessary for withdrawing the 90 locking section from beneath the article. If 95 so desired, the flap portion 9 may be extended downwardly in the garment pocket at the outer side of the pocket portion 8 and then looped beneath the pocket portion so that the locking section 14 is disposed between the rear wall of the pocket portion at the inner wall 5 of the garment pocket. It will also be seen that when the supplemental 100 pocket is secured within the regular garment pocket, that two independent compartments are formed, one by the usual garment pocket and one by the supplemental pocket portion 8.

105 As a further adaptation of the safety device and as will readily be obvious upon observing Figure 2, the pocket portion 8 may be dispensed with and the flap portion 9 secured to the inner side of the garment pocket as by the stitching 28 so that the usual garment pocket will receive the article 110 and the flap 9 serves as a retaining means for the article by looping the minor flap section 14 beneath the article disposed in the usual garment pocket. It will further be apparent that the flap portion 9 may 115 either be secured to the inner wall 5 or the outer wall 6 of the usual garment pocket so that the major flap section 13 may extend at either side of the article to be retained in the garment pocket. In either case, the 120 125 130

flap section 13 will extend across the upper side of the article being positioned in the pocket.

It will also be apparent that if so desired 5 the front and rear walls 16 and 15 respectively of the pocket portion 8 may both be secured at their upper ends to the walls of the garment pocket when it is desirable that two independent pocket compartments are 10 not formed by positioning of the supplemental pocket within the usual garment pocket.

From the foregoing description it will be apparent that a novel and improved safety 15 supplemental pocket for use in connection with ordinary garment pockets has been provided, embodying features whereby articles positioned within the pocket will be securely held against loss and possible theft, and 20 which device may be readily applied to garment pockets without alteration of the usual appearance of the pocket, and which supplemental pocket will not reduce the capacity of the garment pocket. It will also be 25 apparent that a novel locking arrangement has been incorporated in the construction of the device whereby the weight of the article serves to retain the flap portion in a substantially locked position over the article. 30 Various changes may be made to the specific form of the invention herein shown and described, without departing from the spirit of the invention or the scope of the following claims.

35 I claim:

1. A supplemental pocket for garment pockets comprising a pocket portion having an open end, and a flexible flap portion extending from the open end of the pocket 40 portion including a major flap section of a length equal to the height of the pocket portion and a minor flap section disposed at the free end of the major flap section. 45 2. A supplemental pocket for garment pockets comprising a flexible pocket portion having an open end, and a flexible flap portion extending from the open end of the pocket portion including a major flap section having an area substantially equal to the 50 area of the pocket portion and a stiffened minor flap section disposed at the free end of the major flap section.

55 3. A supplemental pocket for garment pockets comprising a flexible pocket portion having an open end, a flexible major flap section extending from the open end of the pocket portion, and a locking flap section arranged at the free end of the major flap section and foldably connected with the major flap section on a line parallel with the 60 open end of the pocket portion.

4. As an article of manufacture a supplemental pocket for garment pockets formed from a single strip of fabric having one end doubled upon itself for forming a pocket portion having an open end extending transversely of the strip, a major flap section extending from the open end of the pocket portion and being of a length equal to the height of the pocket portion, and a minor 65 flap section at the free end of the major flap section and formed with a double thickness of the fabric whereby the minor flap section will be substantially thicker than the major 70 flap section. 75

5. A supplemental pocket for garment pockets comprising a fabric pocket portion having an open end, and a fabric flap portion formed integral with and extending from the open end of the pocket portion including a major flap section and a minor flap section having a double ply of the fabric, said minor flap section having a sewed fold at its connection with the major flap section and having a stiffening stitching extending 80 in a zig-zag formation across the minor section. 85

6. In combination with a garment pocket, a flexible supplemental pocket including a pocket portion fitting within the garment pocket and having an open upper end, a flap portion extending from the open end of the pocket portion and being of a length greater than the height of the pocket portion, and means for securing the supplemental pocket 90 against withdrawal from the garment pocket. 95

7. In combination with a garment pocket, a flexible supplemental pocket including a pocket portion fitting within the garment pocket and having an open upper end, a flexible flap portion extending from the open end of the pocket portion including a major flap section of a length equal to the length 100 of the pocket portion and a minor flap section disposed at the free end of the major flap section, and means for securing the supplemental pocket within the garment pocket along a point adjacent the juncture of the flap and pocket portions. 105

8. In combination with a garment pocket having inner and outer walls and provided with an open upper end, a flap secured adjacent one end to one wall of the pocket adjacent the upper open end, said flap including a major flap section of a length substantially 110 equal to the height of the pocket and a minor flap section disposed at the free end of the major flap section and being of a nature substantially thicker than that of the major flap section. 115
